UNITED STATES PATENT OFFICE.

THOMAS H. SPEAKMAN, OF WARE, ASSIGNOR OF ONE-HALF TO GEORGE DRAPER & SONS, OF HOPEDALE, MASSACHUSETTS.

TRAVELER-CLEARER FOR RING-SPINNING FRAMES.

SPECIFICATION forming part of Letters Patent No. 398,550, dated February 26, 1889.

Application filed January 15, 1889. Serial No. 296,401. (No model.)

To all whom it may concern:

Be it known that I, THOMAS H. SPEAKMAN, of Ware, county of Hampshire, State of Massachusetts, have invented an Improvement in 5 Traveler-Clearers for Ring-Spinning Frames, of which the following description, in connection with the accompanying drawings, is a specification, like letters on the drawings representing like parts.

10 In ring-spinning machines prior to my invention the traveler has been cleared by devices attached to the ring rail or holder, all of which required some considerable trouble in their production and application.

15 In accordance with my invention the clearer is made as a band and surrounds the neck of the ring just below its race, the said band being preferably of wire-like material capable of being sprung upon the ring and having an 20 upwardly-extended projection or finger.

My invention consists of a traveler-clearer composed of a spring-band to surround the neck of the ring and having an upwardly-extended arm.

25 Figure 1 in side elevation shows a spinning ring and holder and one of my improved traveler-clearers, and Fig. 2 a section of Fig. 1 in the dotted line *x*.

The holder *a*, the double-flanged ring *b* 30 held by it, and the traveler *c* are all as usual, and so need not be further described.

To make my improved clearer *d*, I take a piece of wire-like metal of a springy nature, and bend it to form a band portion, 2, to be sprung about and embrace the ring snugly, 35 and bend one end of the metal up, as shown in Fig. 1, to form a finger, 3, which stands up just outside the race of the ring, so that the lint extended from and clinging to the traveler on its rotation strikes against the finger 3, and 40 is by the finger removed from the traveler.

I should consider as within the term "wire-like material" a clearer cut out from sheet metal and bent into the form shown.

I claim—

1. The herein-described traveler-clearer consisting of wire-like material shaped to form a band to embrace the neck of the ring, and having a projection or finger, 3, substantially as described. 45

2. The combination, with the ring, of a clearer consisting of a spring-band having a finger, 3, substantially as described. 50

In testimony whereof I have signed my name to this specification in the presence of two subscribing witnesses. 55

THOMAS H. SPEAKMAN.
